UNITED STATES PATENT OFFICE.

ISAAC LEVY, OF NEW YORK, N. Y., ASSIGNOR TO THE NEW YORK CONSOLIDATED CARD COMPANY, OF SAME PLACE.

DESIGN FOR THE BACK OF A PLAYING-CARD.

SPECIFICATION forming part of Design No. 16,218, dated September 1, 1885.

Application filed June 30, 1885. Term of patent 7 years.

To all whom it may concern:

Be it known that I, ISAAC LEVY, of the city, county, and State of New York, have invented a new and original Design for the Backs of Playing-Cards, of which the following is a description.

Reference is to be had to the accompanying drawing, forming a part of this specification, and which represents my new design.

10 The leading feature of my design consists of the dots having each eight short radial lines, and placed in the centers of squares formed by the intersection of pairs of parallel lines having at their points of intersection square dots, each surrounded by four larger dots placed in the angles of the said squares.

15 The center thus described is surrounded by a border consisting of a wide line having two narrow lines along its inner edge and two narrow lines along its outer edge.

I claim—

20 1. The design for the backs of playing-cards

herein shown and described, the same consisting of the dots having each eight short radial lines, and placed in the centers of squares formed by the intersection of pairs of parallel lines having at their points of intersection dots, each surrounded by four larger dots placed in the angles of the said squares.

2. The design for the backs of playing-cards herein shown and described, the same consisting of the border formed of a wide line having two narrow lines along its inner edge and two narrow lines along its outer edge, the whole surrounding a center formed of a series of squares having at their centers dots, each provided with eight short radial lines, and having at their angles dots, the said squares being separated by pairs of parallel lines having small dots at their points of intersection.

ISAAC LEVY.
